UNITED STATES PATENT OFFICE.

JOHN P. COLEMAN, OF EDGEWOOD, PENNSYLVANIA, ASSIGNOR TO THE UNION SWITCH AND SIGNAL COMPANY, OF SWISSVALE, PENNSYLVANIA, A CORPORATION OF PENNSYLVANIA.

RAILWAY SIGNAL MECHANISM.

No. 863,263.

Specification of Letters Patent.

Patented Aug. 13, 1907.

Application filed March 13, 1907. Serial No. 362,127.

To all whom it may concern:

Be it known that I, JOHN P. COLEMAN, a citizen of the United States, residing at Edgewood, in the county of Allegheny and State of Pennsylvania, have invented 5 certain new and useful Improvements in Railway Signal Mechanisms, of which the following is a specification.

My invention relates to railway signals, and particularly to that class of railway signals, the signal device of which is adapted to give three indications.

10 I will describe a railway-signal embodying my invention and then point out the novel features thereof in claims.

In the accompanying drawings, Figure 1 is a view, partly in vertical section, partly in elevation and partly 15 broken away, of a mechanism embodying my invention and showing the parts in the position they occupy when the signal device indicates danger. Fig. 2 is a similar view showing the parts in their intermediate position. Fig. 3 is a similar view showing the 20 parts in the position they occupy when the signal device indicates safety. Fig. 4 is an elevation, partly broken away, of a modified form of signal device; and Fig. 5 is a vertical sectional view of Fig. 4.

Similar characters of reference designate corresponding parts in all the figures.

A designates a post or other suitable support, and B a signal device supported thereby.

The signal device B is here shown as being of the semaphore type and as comprising a blade b and a spectacle-casting b¹, to which the blade is secured, and which 30 also serves as a counterweight for the blade b. The spectacle-casting b¹ may be formed to carry as many lenses b² as desired in order that the signal device may be employed to give indications at night in connection 35 with a lamp. The casting b¹ is fixed upon a shaft suitably journaled on the post, which shaft carries an arm b³, to which one end of an up and down rod b⁴ is connected. The lower end of the rod b⁴ is pivotally connected to an operating mechanism D. As here 40 shown, this mechanism is of the fluid pressure type and comprises a cylinder d and piston d¹. The mechanism D is supported by a cylinder d² of a similar fluid pressure mechanism D¹. The piston d³ of the mechanism D¹ is fixed, being supported in any suitable manner on 45 a base d⁴. Fluid pressure is supplied to the mechanisms D and D¹ from any suitable source, as through a pipe D² and such fluid pressure is under the control of electrically operated valve devices E and E¹. The valve devices may conveniently be substantially of the 50 form and arrangement illustrated and described in Letters Patent No. 357,109, issued February 1, 1887, to George Westinghouse, Jr. for electrical interlocking mechanism for switches and signals, to which reference may be had for the details of construction and operation.

It is only necessary to here state that each electrically operated valve device has the functions of opening the supply of fluid pressure when the magnet comprised therein is energized and of shutting off or closing the supply of fluid pressure when the magnet comprised 60 therein is deenergized and to open an exhaust port or passage to the atmosphere.

The stems of the pistons d¹ and d³ are tubular and communicate at their lower ends with passages d¹¹, d¹², respectively, controlled by the valve devices E 65 and E¹ respectively, and the supply pipe D² also communicates with the passage d¹² controlled by the valve device E¹. At their upper ends the tubular stems communicate with the cylinders d and d² above the pistons. The lower end of the stem of the piston d¹ communicates 70 with the upper end of the cylinder d² by means of a passage d¹³ controlled by the valve device E.

As shown in Fig. 1 the signal device indicates danger and the fluid pressure operating mechanisms are in their normal positions, and the valves e and e¹, controlled respectively by the electrically-operated valve devices E and E¹ are in position to prevent the passage 75 of fluid pressure to the cylinders and to open communication between the interior of the cylinders and exhaust ports. If now the valve device E¹ be energized 80 by the closing of a circuit, the valve e¹ will be shifted to close the exhaust port and open communication between the supply pipe D² and the interior of the cylinder d² by way of the tubular stem of the piston d³, and since the said piston is fixed the cylinder d² will be 85 moved upwardly to the position shown in Fig. 2 and will carry with it the fluid pressure operating mechanism D and the electrically-operated valve device E, both of which are supported on the cylinder d² to move positively therewith in both directions vertically. 90 This movement will move the rod b⁴ upwardly to sufficient extent to move the signal device to the caution position, as indicated in Fig. 2. In such position the valve e will prevent any fluid pressure passing from the cylinder d² to the cylinder d through the passage d¹³ and 95 will continue to do so until the valve device E is energized to move the valve e. If now the valve device E be energized the valve e will be shifted to close its exhaust port and open communication between the cylinder d² and cylinder d by way of the passages d¹³, d¹¹ and 100 tubular stem of the piston d¹ and this will cause the cylinder d to move upwardly to the position indicated in Fig. 3 and thereby move the rod b⁴ still further upwardly and shift the signal to the clear position of indication as shown in Fig. 3. Obviously, by deenergizing the 105 valve devices E and E¹ the valves e and e¹ will be moved to open the exhaust ports and close the supply passages and the signal will automatically move to danger position and the fluid pressure operating mechanism to the positions shown in Fig. 1.

I have not deemed it necessary to illustrate or describe any circuits or source of electrical supply for the valve devices E and E¹.

The railway signal may be used in "block signaling systems" wherein the operation of the signals is automatically controlled by the movements of trains over the blocks.

Reference may be had to U. S. Patent, No. 729,065, granted May 26, 1903, to M. D. Hanlon, which shows one arrangement of circuits, etc., which might be used in connection with the electrically operated valve devices E and E¹, and in which patent the devices marked E, E, are substantially the same as devices E and E¹. Of course, the railway signal may also be used in other connections, for example, in interlocking plants.

In Fig. 4 I have shown a signal device B¹ in which the blade b is designed to move above the horizontal to the caution and clear positions of indication instead of below it as in Figs. 1, 2 and 3. Here the post or support A¹ is shown as tubular and in order to adapt my invention for use in connection with this type of signal device the shaft which carries the signal device is journaled in a box or casing C, secured to or forming a part of the tubular post A¹, and provided with a pinion c with which a pivoted quadrant c¹ meshes. The quadrant is provided with an arm c² pivotally connected to the upper end of the rod b⁶ which, as shown, extends up through the tubular post or support A¹. When the rod b⁶ is moved upwardly as heretofore described the arm c² will move to the two positions indicated by dotted lines in Fig. 5, and the signal blade b will be moved to the positions indicated by dotted lines in Fig. 4.

It will be noted that the operation of the cylinder d for moving the signal device to indicate "clear" is dependent upon the operation of the cylinder d² to move the signal device to indicate caution. This is due to the fact that the supply of air to the cylinder d is obtained through and from the cylinder d², and therefore the movement of the cylinder d is dependent upon the supply of fluid pressure to the cylinder d².

An important advantage of the above described construction is that stuffing boxes and packing for the piston stems are dispensed with and the only packing necessary is that for the pistons.

What I claim as my invention is:

1. In a railway signal, the combination of a signal device, a plurality of fluid-pressure mechanisms for moving the signal device to different positions of indications, said mechanisms each comprising a cylinder and a piston and the cylinders being movable with respect to the pistons, the piston of one mechanism being fixed and the other mechanism being supported by the cylinder coöperating with the fixed piston, a connection between the cylinder of the last named mechanism and the signal device, and valve devices for controlling the admission of fluid pressure to the cylinders.

2. In a railway signal, the combination of a signal device, a plurality of fluid pressure mechanisms for moving the signal device to different positions of indications, said mechanisms each comprising a cylinder, a piston and a tubular piston stem, and the cylinders being movable with respect to the pistons, the piston of one mechanism being fixed and the other mechanism being connected to and movable as an entirety with the cylinder coöperating with the fixed piston, a fluid pressure supply pipe connected by a passage with the tubular stem of the fixed piston, and the cylinder coöperating with said fixed piston being connected by a passage to the tubular stem of the piston of the other mechanism, a connection between the cylinder of the last named mechanism and the signal device, and separate valve devices for controlling the flow of fluid pressure through said passages.

3. In a railway signal, the combination with a signal device having a bias to one position of indication, of means for moving it against its bias to two other positions of indication, said means comprising two pistons and cylinders and an electrically operated valve for each for controlling the supply of fluid pressure thereto, one of said cylinders receiving its supply of fluid pressure through the other cylinder and only when the electrically operated valve of said other cylinder is energized.

4. In a railway signal, the combination with a signal device having a bias to one position of indication, of means for moving it against its bias to two other positions of indication, said means comprising two cylinders arranged in tandem and in communication with each other through a passage, a piston in each cylinder, and an electrically operated valve for each cylinder one of said valves being adapted to control said passage between the two cylinders.

In testimony whereof I have signed my name to this specification in the presence of two subscribed witnesses.

JOHN P. COLEMAN.
